(57) **CLAIM**

The ornamental design for a sole for a metal wood type golf club head, as shown and described.

DESCRIPTION

FIG. 1 is a bottom perspective view from the side of a sole for a metal wood type golf club head showing my new design.

FIG. 2 is a bottom plan view thereof.

FIG. 3 is a rear view thereof.

FIG. 4 is a front view thereof.

FIG. 5 is a toe side view thereof; and,

FIG. 6 is a heel side view thereof.

The broken line showing is included for the purpose of illustrating and forms no part of the claimed design.
